THERMOSENSITIVE DEVICE FOR HEAT-MOTORS WITH LAGGING-JACKETS.

No. 824,858.

Specification of Letters Patent.

Patented July 3, 1906.

Application filed June 1, 1903. Serial No. 159,677.

To all whom it may concern:

Be it known that I, WESTON M. FULTON, a resident of Knoxville, Tennessee, have invented a new and useful Improvement in Thermosensitive Devices for Heat - Motors with Lagging - Jacket, which invention is fully set forth in the following specification.

This invention relates to motors, and more particularly to motors operable as the result of changes in atmospheric temperature. All heat - motors consist, essentially, of two parts—viz., some device sensitive to heat and cold and some movable part or parts operated by said thermosensitive device. This invention relates to the thermosensitive device.

It has been heretofore proposed to confine an expansive agent in an expandible and collapsible vessel and utilize the expansion and contraction of the vessel due to the increase or decrease in volume of the expansive agent with changes in temperature as a means for obtaining motive power. Where the range of temperature is very great—as, for example, in the case of atmospheric temperature—it has been necessary to provide a large range of expansion and contraction of the vessel in order that slight changes in temperature may produce any material change in volume of the vessel.

My invention has for its object the construction of a device which will give great extent of motion with slight temperature changes and which will at the same time oscillate back and forth between certain fixed limits regardless of how high or how low the temperature may go. With this object in view it consists in connecting together two collapsible and expandible vessels, each containing an expansive agent, and providing a heat-lagging jacket for one of the vessels, so as to render it sluggish to changes of temperature which may take place outside of the lagging-jacket, thereby giving its temperature variations a lag relatively to the variations of the temperature of the atmosphere. I prefer to employ a saturated vapor as the expansive agent in the vessels; but any other suitable expansive agent may be used.

One form which the inventive idea may assume is illustrated in the accompanying drawing, which is a central vertical section of a thermosensitive device made according to the present invention.

In said drawing, 1 is an expansive and collapsible vessel having rigid end walls 3 and 4 and flexible lateral walls 5, and 2 is a like vessel having rigid end walls 6 and 7 and flexible lateral walls 8. The vessel 1 is inclosed in a thick jacket of some heat-retarding substance, as animal hair or wool 9, packed between retaining-walls 10 and 11, the interior dimensions of the latter being larger than vessel 1, so as to afford room for the expansion thereof. The rigid end walls 4 and 7 of the respective vessels 1 and 2 are firmly secured to the respective inner and outer walls of the lagging-jacket, and the walls 3 and 6 of said vessels are connected by rods 12 13, preferably composed of some substance which is not a ready conductor of heat, as wood. Secured to the rigid end wall 6 of vessel 2 is a rod or cable 14, which may be connected in any suitable way to the movable parts which the device is designed to operate.

In order that the device may operate to the best advantage, the pressure of the expansive agent in one vessel should exactly balance that in the other when both vessels are at the same temperature. Where it is desirable to have the vessels unequal in diameter, an equality of pressure may be obtained by the proper selection of expansive agents. I, however, prefer to have the vessels of equal diameter, so that the surface area of wall 3 shall be equal to the surface area of wall 6. Both vessels may then be charged with the same kind of expansive agent. For example, suppose the vessels 1 and 2 to be of equal diameter and be charged with an expansive agent, preferably a saturated vapor, as boron trichlorid, ethyl chlorid, or ethylene oxid, all of the air having been first expelled from the vessels. Then when both vessels are at the same temperature the pressure exerted by the vapor upon wall 3 will just equal the pressure on wall 6. Now suppose the temperature of the atmosphere to change—*e. g.*, rise. Then vessel 1, being inclosed in the heat-retarding jacket, will not be immediately affected by the change, but vessel 2, being exposed directly to the atmosphere, will immediately become warmer, and the pressure of the vapor therein will become greater than the pressure of the vapor in vessel 1. This will cause vessel 2 to expand,

thereby forcing vessel 1 to collapse, and since saturated vapors change in volume without change in tension the expansion of vessel 2 and contraction of vessel 1 will continue until the respective vessels have reached their limits of expansion and contraction. By making the vessels sufficiently long I am thus enabled to obtain as much motion as I please with slight changes in temperature. It is evident that when the temperature of the atmosphere falls the temperature of vessel 1 will lag behind the temperature of vessel 2, and the latter becoming cooled below the temperature of the former will be forced to collapse by the greater pressure of the former. By properly regulating the thickness of the lagging-jacket the temperature of vessel 1 may be made to lag behind that of vessel 2 just sufficiently to obtain the best results. It is to be understood that I use the term "saturated vapor" in its well-known technical sense—viz., a vapor in the presence of its own liquid.

Having thus described the invention, what is claimed is—

1. The combination of an expandible and collapsible vessel containing an expansive agent and protected from variations in temperature, with an expandible and collapsible vessel containing an expansive agent and exposed to variations in temperature, and means connecting movable parts of said vessels.
2. The combination of an expandible and collapsible vessel containing a saturated vapor and protected from variations in temperature,

ture, with an expandible and collapsible vessel containing a saturated vapor and exposed to variations in temperature, and means connecting movable parts of said vessels.

3. The combination of two connected expandible and collapsible vessels each containing an expansive agent, and a heat-retarding jacket surrounding one of said vessels.

4. The combination of two connected expandible and collapsible vessels each containing a saturated vapor, and a heat-retarding jacket surrounding one of said vessels.

5. The combination of two expandible and collapsible vessels each containing an expansive agent, means isolating one vessel from the influence of atmospheric temperature, and non-heat-conducting connections between movable parts of said vessels.

6. The combination of a jacket or casing composed of non-heat-conducting material, an expandible and collapsible vessel within said casing and having rigid end walls one of which is secured to a wall of the casing, a second expandible and collapsible vessel without said casing and having rigid end walls one of which is secured to a wall of said casing and means connecting the free end walls of said vessels.

In testimony whereof I have signed this specification in the presence of two subscribing witnesses.

WESTON M. FULTON.
